Primary Examiner—Martie Thompson*Assistant Examiner*—Robert M. Spear*Attorney, Agent, or Firm*—Harold H. Dutton, Jr.; W. Charles L. Jamison; Diane F. Liebman[57] **CLAIM**

The ornamental design for a telescopic mail box, as shown and described.

DESCRIPTION

FIG. 1 is a perspective view of a telescopic mail box showing my new design;

FIG. 2 is a right side elevational view thereof;

FIG. 3 is a right side elevational view thereof in a retracted state;

FIG. 4 is a left side elevational view thereof;

FIG. 5 is a left side elevational view thereof in a retracted state;

FIG. 6 is a top plan view thereof;

FIG. 7 is a top plan view thereof in a retracted state;

FIG. 8 is a bottom view thereof;

FIG. 9 is a front view thereof; and,

FIG. 10 is a rear view thereof.

The broken line showing of a mailbox mounting post is for illustrative purposes only and forms no part of the claimed design.
